United States Patent Office.

JAMES T. SMITH, OF WASHINGTON, DISTRICT OF COLUMBIA.

Letters Patent No. 99,019, dated January 18, 1870.

IMPROVEMENT IN NUMBER-PLATES FOR DOORS, &c.

The Schedule referred to in these Letters Patent and making part of the same.

To all whom it may concern:

Be it known that I, JAMES T. SMITH, of Washington, in the county of Washington, and District of Columbia, have invented a new and valuable Improvement in Means of Constructing and Arranging Tactile Representations of Numbers; and I do hereby declare that the following is a full, clear, and exact description of the construction and operation of the same, reference being had to the annexed drawings, making a part of this specification, and to the letters and figures of reference marked thereon.

Figure 1 of the drawings is a representation of a door-plate, with bosses attached, showing one mode of arrangement.

Figure 2 is a door-plate, showing another mode of arranging the bosses.

Figure 3 is a series of raised figures, with bosses thereon.

Figures 4 and 5 represent a door-knob.

My invention has relation to means for indicating the numbers of dwellings, streets, buildings, and other things known or designated by figures; and

It consists in providing novel means by which the actual numbers of such streets, tenements, or things may be known, by the touch of the inquirer.

The drawings represent both raised and painted numerals, together with a door-knob and door-plates, with raised conical ball or other shaped protuberances thereon, which I denominate bosses. These bosses may be cast with the raised figures, plates, or knobs, or they may be formed in the shape of pins, with heads attached, and driven into such plates, knobs, or figures. They may also be united with such plates, knobs, or figures, by solder or other suitable means of attachment.

I sometimes attach these bosses to the front side of the knob, sometimes to its periphery, and sometimes to the rear side thereof, as shown on fig. 5 of the drawings. I sometimes place these bosses on a door or other part of a building or room, to indicate its number, and also upon a lamp or other post, to indicate the number of a street.

The bosses above mentioned are marked *a* on the drawings, and intended to represent, by their numbers and positions, the actual number of the tenement or other thing to which they are attached.

For example, upon the numeral 1, I affix one boss; upon the numeral 2, two bosses, and so on, to and in-

cluding the numeral 9, the number of said bosses always indicating, by their sum total, the figure upon which they are placed. The cipher may be indicated by ten bosses, but upon raised figures they may be omitted from the cipher. When the figures are merely painted, and not raised, ten bosses upon the cipher will be required. I sometimes, however, indicate the cipher by means of a bar, as shown at *c*, on fig. 4 of the drawings.

Upon door-plates and knobs the bosses are arranged, either as shown on figs. 1 or 2, or 4, or in an equivalent manner, according to the taste of the manufacturer. As arranged on fig. 1, they indicate 548; upon fig. 2, they read 375; and upon fig. 4, they stand for 4,520, the bar *c* being used in the place and stead of a cipher.

The reading should always commence on the left-hand side of the plate, knob, figure, or series of figures.

Depressions or grooves of any suitable forms in the plates, figures, or knobs, may be made to serve the same purpose as bosses, and in some positions they are found desirable, but for ordinary use I recommend the bosses, as described.

The bosses possess at least this advantage over grooves: when made of shining metal, and kept well polished, they are discernible by the eye, and may be read whenever a faint gleam of light is upon them.

My device will enable an inquirer to ascertain the number of any tenement, room, or street, even when shrouded in intense darkness, and a blind man may also find such number through its agency.

My device is not only applicable to tenements and streets, but also to cars, hacks, express-wagons, carriages, travelling-trunks, baggage-checks, and generally to anything that can be indicated by numbers.

I claim, as my invention—

The method of arrangement of the raised or depressed indicators upon plates, knobs, or figures, as herein described, substantially as and for the purposes specified.

In testimony that I claim the above, I have hereunto subscribed my name, in the presence of two witnesses.

JAMES T. SMITH.

Witnesses:
